UNITED STATES PATENT OFFICE.

JAMES N. WHITE, OF DENVER, COLORADO.

ROTARY LAUNDRY MACHINE.

Application filed March 3, 1927. Serial No. 172,383.

This invention relates to rotary cylindrical laundry machines and has for an object the provision, in such a machine, of adjustable partitions for dividing the cylinder into compartments of any desired relative sizes whereby a plurality of washings of any variety of sizes may be handled in said machine coincidently, while keeping the lots separated and maintaining the balance of the cylinder to prevent wabbling during revolution thereof.

Herein I have illustrated the invention in its preferred form as incorporated in a laundry machine having a vertical cylinder with perforated sides through which perforations the water from the contained laundered articles is thrown out by centrifugal force when the cylinder is rotated on its center bearing, for drying the contained articles.

Other objects will appear from the following specification and claims and the accompanying drawing in which like reference characters indicate corresponding parts throughout and in which

Figure I is a view of a rotary cylindrical laundry machine with the invention installed therein, the lower portions being shown in elevation and the upper portion in section on line A—A in Figure II.

Figure II shows a section on line B—B Figure I.

Figure III is a detail view of one of the partitions.

The machine illustrated in the drawing is of common type, having a casing or tank 1 with a screen, removable top 1^a supported by and commonly formed integral with standards 2 rising from base 3 and provided with a drain 4. Within the casing or tank 1 is a cylinder 5 having perforations 6, a central opening 7 in the top, the cylinder being mounted upon the upper end of shaft 8 to revolve therewith, the shaft being revolvably mounted in a seat 9 and having a revolvble water tight mounting through the bottom of the casing as shown generally at 10 and carrying a pulley 11 for belt 12 connected with any suitable source of power, not shown.

Shaft 8 is provided with a central bolt 13 projecting up through and above the bottom of cylinder 5 and threaded for reception of nut 14 for holding the cylinder tightly on shaft 8. A washer 15 may be provided. Thus far the description is of the common machine in which wet clothes placed in the cylinder are dried by having the water forced

therefrom through perforations 6 by centrifugal force upon the rapid revolution of the cylinder by belt 12 revolving shaft 8.

In laundry work it is frequently necessary to handle small lots of clothes keeping each lot separated from other lots during the washing and drying. The machines are, and for general utility should be, large enough to accommodate within the cylinder a large lot of clothes. To use such a large machine for a single small lot is uneconomical but to place a plurality of small lots in the cylinder involves danger of mixing the lots, destroying their separate identity. It is, therefore, desirable to provide means whereby a plurality of small lots of clothes may be handled in and by the machine coincidently while keeping the lots separated. It is also necessary that the arrangement be such that the contents of the cylinder shall be always well balanced in order not to cause wabbling during rapid revolution and for economy and efficiency the arrangement should be adjustable according to the various sizes of the respective lots of clothes.

To meet these requirements I provide a plurality of partitions 16, carried by and upstanding from plates 17, preferably of substantially triangular shape and having means as holes 18 for revolvably mounting the same on bolt 13. The plates 17 lie at and substantially parallel with the bottom of cylinder 5 and the partitions preferably stand substantially perpendicular thereto.

Preferably a collar 19 with a flange 20 is positioned on the bolt 13 under the nut, and washer 14 and 15 and the holes 18 are made large enough to fit over the collar. The plates 17 and partitions 16 are mounted with sufficient looseness to permit of their easy manual movement around the central mounting so that they may all be nested together in case of the use of the machine for a single large lot of clothes or be separated so as to form a plurality of compartments of the various desired sizes within the cylinder (as clearly illustrated at Figure II) for the accommodation, while preserving the separateness of, a plurality of small lots of clothes of various sizes.

The plates 17 are important. The clothes placed in a compartment along the bottom of which a plate extends, lie upon such plate and the weight of the clothes holds the plate 17, and thereby its partition 16, in position as placed. Generally the clothes will lie

partly upon the plate and partly upon the bottom of the cylinder which tends still more to hold the plate and its partition from displacement. Partitions carried by underlying plates may be notched as at 21 to accommodate overlying plates.

It will be apparent that with partitions constructed and mounted substantially as described, a cylinder may be used as a single compartment or may be divided into any desired number of compartments not exceeding the number of partitions and that compartments may be varied in size from one small enough for the smallest single piece of cloth to be handled, up to the full capacity of the cylinder and that by adjustment of the sizes of compartments according to the sizes of lots of clothes to be handled, a balance of the cylinder may be easily maintained and wabbling thereby prevented.

Variation of details of construction, within the spirit of the invention and scope of the claims will occur to those skilled in the art.

25 I claim—

1. In a cylindrical centrifugal drier, partitions mounted within the cylinder and independently revoluble around its axis for dividing the cylinder into longitudinal compartments.

2. In a cylindrical centrifugal drier,

35 plates mounted within the cylinder for revolution around its axis in a plane near and substantially parallel to the bottom of the cylinder and partitions carried by the plates for dividing the cylinder into longitudinal compartments.

3. In a cylindrical centrifugal drier, plates mounted within the cylinder for revolution around its axis in a plane near and 40 substantially parallel to the bottom of the cylinder and partitions carried by the plates for dividing the cylinder into longitudinal compartments, said plates with their respective partitions being adapted to nest together.

4. In a cylindrical centrifugal drier, partitions mounted within the cylinder and revoluble around its axis for dividing the cylinder into longitudinal compartments, and plates connected with said partitions and adapted to lie adjacent to and in a plane substantially parallel with one of the walls of the cylinder.

5. In a cylindrical centrifugal drier, partitions mounted within the cylinder and independently revoluble around its axis for dividing the cylinder into longitudinal compartments adjustable as to size.

55 In testimony whereof, I affix my signature.

60 JAMES N. WHITE.
